ROLL CONSTRUCTION

John L. Drake, Toledo, Ohio, assignor to Libbey-
Owens-Ford Glass Company, Toledo, Ohio, a
corporation of Ohio

Application July 11, 1932, Serial No. 621,820

20 Claims. (Cl. 257—95)

The present invention relates broadly to roll constructions and more particularly to improvements in fluid cooled rolls adapted primarily for use in the manufacture of sheet or plate glass.

5 An important object of this invention resides in the provision of novel means for effecting a more accurate and uniform cooling of the rolls employed in the formation of sheet glass, whereby to prevent or minimize the tendency thereof 10 to warp and thereby assist in the formation of a sheet of more uniform thickness and flatness.

Another object of the invention resides in the provision of cooling means designed to effect a relatively greater cooling action upon the roll at 15 the center thereof than at its opposite ends.

A further object of the invention resides in the provision of cooling means adjustable with respect to the roll casing for localizing or concentrating the cooling action upon any desired 20 portion of the periphery of the roll circumferentially thereof.

Other objects and advantages of the invention will become more apparent during the course of the following description when taken in connection 25 with the accompanying drawings.

In the drawings forming a part of this application and wherein like numerals are employed to designate like parts throughout the same,

Fig. 1 is a vertical longitudinal section through 30 a portion of one type of sheet glass forming machine showing the present invention incorporated therewith,

Fig. 2 is a vertical transverse section partially in elevation, of one end of a pair of sheet forming rolls, showing the means for supplying the cooling fluid thereto,

Fig. 3 is a longitudinal section through the central portion of one of the forming rolls,

Fig. 4 is an elevation of one of the adjusting 40 plates, and

Fig. 5 is a view of approximately one-half of the cooling fluid supply member flattened out or developed to show the arrangement of the openings for the distribution of the cooling fluid.

45 Although it is to be expressly understood that the fluid cooled roll herein provided is not limited to use in connection with any particular type of sheet glass forming apparatus, yet it has been illustrated in Fig. 1 of the drawings, by way of example, in association with the well known Bicheroux type of machine which is adapted for the intermittent formation of successive sheets of glass.

Briefly stated, this machine embodies in its 50 construction a receiver 10 within which the

charge of molten glass 11 to be reduced to sheet form is poured. Associated with one end of the receiver are the two forming rolls 12 and 13 respectively spaced from one another to create a sheet forming pass therebetween. The charge 5 of molten glass 11 is moved from the receiver 10 through the sheet forming pass wherein it is reduced by the rolls to a sheet 14 of substantially uniform and predetermined thickness. As the sheet leaves the forming rolls, it is received upon 10 an inclined apron or runway 15 and, while still plastic, is deflected into the horizontal plane and conveyed by means of the rolls 16 or other suitable conveying means to an annealing leir wherein it is annealed and the temperature thereof 15 gradually reduced as is well known in the art.

Each of the forming rolls 12 and 13 comprises, as best shown in Fig. 3; a cylindrical casing 17 preferably of uniform diameter and which may be made of either cast iron or some suitable non- 20 corrosive metal. Carried at the opposite ends of the casing 17 are the end portions 18 and 19 respectively. The forming rolls 12 and 13 are rotatably supported at each end by the bearings 20 and 21 respectively (Fig. 2) within which the 25 corresponding end portion 18 or 19 is journaled. One of the forming rolls, and as here shown the roll 13, is adapted to be positively driven and, for this purpose, may carry at one end thereof a gear 22 driven by any suitable 30 driving mechanism, the roll 12 being preferably driven from roll 13 by intermeshing gears 23 and 24 (Fig. 1) carried at the ends of the roll remote from gear 22.

Each forming roll is hollow and provided with 35 a continuous bore therethrough open at its opposite ends. This bore is of a substantially uniform diameter throughout the entire length of casing 17 to provide a chamber 25, while that portion of the bore extending through each end 40 portion 18 and 19 tapers outwardly from the chamber as at 26 and terminates in a cylindrical portion 27 of a relatively smaller diameter.

45 Mounted within the chamber 25 of each roll casing 17 is a cylindrical tubular member 28 provided with a relatively large number of small openings communicating with the interior of the casing as will be more fully hereinafter described. This tubular member is maintained spaced from the inner wall of the casing and 50 cooperates therewith to define a passageway 29 therebetween for the passage of the cooling fluid. The tubular member 28 is provided with the imperforate tapering end portions 29 and 30 respectively which are received within the ta- 55

pered portions 26 of the roll bore and which terminate in cylindrical end portions 31 and 32 received within the cylindrical portions 27 of said bore.

5   Mounted within the tubular member 28 is an imperforate shell 33 spaced from and cooperating with said tubular member to define a passageway 34 therebetween. Carried at the opposite ends of the shell are the imperforate conical 10 end portions 35 and 36 respectively which are received within the tapered end portions 29 and 30 of the tubular member 28. The shell 33 is maintained in a definite predetermined relation with respect to tubular member 28 and is secured thereto in any suitable manner such as by welding or the like.

The cylindrical end portions 31 and 32 of each tubular member 28 project beyond the opposite ends of the roll casing 17 as indicated at 37 in 20 Fig. 2, with each projecting end portion being supported within a bearing 38 carried by a bearing housing 39. This housing is divided by a vertical partition wall 40 to provide an inlet chamber 41 and an outlet chamber 42. Communicating with the inlet chamber 41 is an inlet conduit 43, while leading from the outlet chamber 42 is an outlet conduit 44. Extending between and connecting the bearing housing 39 with the roll casing 17 is a sleeve 45 spaced from and cooperating with the projecting end portion 37 of the tubular member 28 to define a passageway 46. The projecting end portion of the tubular member 28 is provided within the inlet chamber 41 with a plurality of inlet openings 47.

In the operation of the invention as thus far described, the cooling fluid such as, for example, water, is adapted to be introduced into the opposite ends of the tubular member 28 and caused to flow from the opposite ends of the casing 17. More specifically, the cooling fluid is introduced into each end of each roll through the inlet conduit 43, the fluid entering the inlet chamber 41 in bearing housing 39 and passing into the tubular member 28 through the openings 47. The cooling fluid flows toward the center of the roll and is deflected by the conical end portions 35 and 36 of shell 43 into the passageway 34 between the shell and tubular member. The cooling fluid then discharges from the tubular member through the openings therein into the casing 17 where it contacts with the inner wall thereof to effect the desired cooling of the roll. The fluid then flows toward the opposite ends of the casing through the passageway 28' between the tubular member and inner wall of the casing, and then discharges from the opposite ends of the casing through passages 46 into the outlet chambers 42 and thence through outlet conduits 44.

60   The present invention also contemplates the provision of novel means for effecting a relatively greater cooling action upon the roll at the central portion thereof than at its opposite ends, and further, for localizing or concentrating the cooling action upon any desired portion of the periphery of the roll circumferentially thereof. These objects are attained by the novel arrangement of the fluid distributing openings formed in the tubular member 28 and further, in the making of the said tubular member rotatable with respect to the roll casing 17.

In Fig. 5, approximately one-half of the tubular member 28 has been flattened out or developed to show the arrangement of the distributing 70 openings through which the cooling fluid

passes from said member into the roll casing. Thus, throughout substantially two-thirds of the circumference of the tubular member, such as for example from points *a* to *b*, the distributing openings 48 are substantially equi-distantly spaced both longitudinally and circumferentially thereof so that a uniform distribution of the cooling fluid is had. In other words, the openings 48 are arranged in a plurality of longitudinally extending parallel rows spaced circumferentially around approximately two-thirds of the circumference of the tubular member. However, throughout the remaining one-third of the circumference of the tubular member, for example from *c* to *d*, the distributing openings 49 are arranged closer together both longitudinally and circumferentially to the end that that portion of the periphery of the roll casing opposite the openings 49 will be given a more localized or concentrated cooling action than that portion of the periphery of the roll casing opposite the openings 48.

The openings 49 are arranged in a plurality of rows extending longitudinally of the tubular member, with the openings in adjacent rows being staggered and the openings in alternate rows in substantial alignment with one another. The rows of openings 49 also diverge from the opposite ends of the tubular member toward the center thereof, and arranged at substantially the central portion of the tubular member between the rows of openings 49 are the additional relatively shorter rows of openings 50, the provision of which effects a greater cooling action at the center of the roll casing than toward the opposite ends thereof. Furthermore, it is preferred that the openings 50 in each row be arranged slightly closer to one another from the outer ends of the row to the center thereof so that the cooling action gradually increases toward and is greatest at the center of the roll.

The tubular member 28 is, as set forth above, rotatably mounted within the casing 17 and, to effect rotation thereof, there is carried at the outer end of each tubular member a hand wheel 51 having a plurality of openings 52 therein. This wheel is secured by means of a fastening element 53 to a plug 54 fitting within and closing the adjacent end of the tubular member. When it is desired to rotate the tubular member, it is simply necessary to turn the hand wheel 51, and this wheel may then be secured in proper adjusted position by means of a securing element 55 passing through one of the openings 52 and received within an opening formed in the portion 56 of the cooling fluid supply means.

In the formation of sheet glass by a rolling operation, such as in accordance with the Bicheroux process referred to above, it is frequently necessary that one portion of the roll periphery be subjected to a relatively greater cooling action than another portion thereof so as to offset a corresponding greater amount of heat whereby to prevent or minimize the tendency of the roll to warp. With the present invention, and simply upon rotation of the tubular member 28, it is possible to concentrate the cooling action upon any desired portion of the periphery of the roll casing in order to obtain a uniform cooling thereof. Furthermore, the rolls usually become hotter at their centers than toward their opposite ends, and with the present arrangement, a localized cooling action is also had at the middle of the roll to compensate for this increased heating. By maintaining the roll at a more uniform tempera- 75

ture and thus preventing or minimizing warpage thereof, it will of course be appreciated that a sheet of more uniform thickness and flatness may be obtained.

5. It is to be understood that the form of the invention herewith shown and described is to be taken as the preferred embodiment of the same, and that various changes in the shape, size and arrangement of parts may be resorted to without departing from the spirit of the invention or the scope of the subjoined claims.

I claim:

1. In combination in a fluid cooled roll, an outer rotatable cylindrical casing, a normally stationary fluid supply member arranged within said casing and having a plurality of openings discharging therefrom, said openings being irregularly spaced to effect a relatively greater cooling action upon one portion of the casing than upon another portion thereof, means for supplying a cooling fluid to said member, and means for rotating said member relative to said casing.

2. In combination in a fluid cooled roll, an outer rotatable cylindrical casing, a normally stationary fluid supply member arranged within said casing and having a plurality of openings discharging therefrom, said openings being arranged to effect a relatively greater cooling action upon one portion of the casing than upon another portion thereof, means for supplying a cooling fluid to said member, means for rotating said member relative to said casing, and means for securing said fluid supply member in adjusted position.

3. In combination in a fluid cooled roll, an outer rotatable cylindrical casing, a normally stationary fluid supply member arranged within said casing and having a plurality of openings discharging therefrom, said openings being arranged to effect a relatively greater cooling action upon one portion of the casing than upon another portion thereof, means for feeding a cooling fluid into the opposite ends of said member, means for conducting said fluid from the opposite ends of said casing, and means for rotating said member relative to said casing.

4. In combination in a fluid cooled roll, an outer rotatable cylindrical casing, a normally stationary fluid supply member arranged within said casing and having a plurality of openings discharging therefrom, said openings being arranged to effect a relatively greater cooling action upon one portion of the casing than upon another portion thereof, means for feeding a cooling fluid into the opposite ends of said member, means for conducting said fluid from the opposite ends of said casing, means for rotating said member relative to said casing, and means for securing said fluid supply member in adjusted position.

5. In combination in a fluid cooled roll, an outer rotatable cylindrical casing, a tubular normally stationary fluid supply member extending through the casing and having a plurality of openings discharging therefrom, said openings being arranged to effect a relatively greater cooling action upon one portion of the casing than upon another portion thereof, a hollow imperforate member arranged within said supply member and maintained in predetermined spaced relation with respect thereto, means for supplying a cooling fluid to said tubular member, and means for rotating said fluid supply member and imperforate member relative to said casing.

6. In combination in a fluid cooled roll, an outer rotatable cylindrical casing, a tubular normally stationary fluid supply member extending through the casing and having a plurality of openings discharging therefrom, said openings being arranged to effect a relatively greater cooling action upon one portion of the casing than upon another portion thereof, a hollow imperforate member arranged within said supply member and maintained in predetermined spaced relation with respect thereto, means for supplying a cooling fluid to said tubular member, means for rotating said fluid supply member and imperforate member relative to said casing, and means for securing the fluid supply member in adjusted position.

7. In combination in a fluid cooled roll, an outer rotatable cylindrical casing, a tubular normally stationary fluid supply member extending through the casing and having a plurality of openings discharging therefrom, said openings being arranged to effect a relatively greater cooling action upon one portion of the casing than upon another portion thereof, a hollow imperforate member arranged within said supply member and maintained in predetermined spaced relation with respect thereto, means for feeding a cooling fluid into the opposite ends of said tubular supply member, means for conducting said fluid from the opposite ends of said casing, and means for rotating said fluid supply member and imperforate member relative to said casing.

8. In combination in a fluid cooled roll, an outer cylindrical casing, a tubular fluid supply member extending through the casing and having a plurality of openings discharging therefrom, said openings being arranged to effect a relatively greater cooling action upon one portion of the casing than upon another portion thereof, a hollow imperforate member arranged within said supply member and maintained in predetermined spaced relation with respect thereto, means for feeding a cooling fluid into the opposite ends of said tubular supply member, means for conducting said fluid from the opposite ends of said casing, and means for rotating said fluid supply member and imperforate member relative to said casing.

9. In combination in a fluid cooled roll, an outer cylindrical casing, a tubular fluid supply member arranged within the casing and having a plurality of openings discharging therefrom, said openings being arranged in a plurality of longitudinally extending rows spaced circumferentially of said member, certain of the rows of openings being closer together than other of said rows of openings whereby to effect a relatively greater cooling action upon one portion of the casing than upon another portion thereof, means for supplying a cooling fluid to said member, and means for rotating said member relative to said casing.

10. In combination in a fluid cooled roll, an outer cylindrical casing, a tubular fluid supply member arranged within the casing and having a plurality of openings discharging therefrom, said openings being arranged in a plurality of longitudinally extending rows spaced circumferentially of said member, certain of the rows of openings being closer together than other of said rows of openings whereby to effect a relatively greater cooling action upon one portion of the casing than upon another portion thereof, a hollow imperforate member arranged within said

fluid supply member and maintained in pre-determined spaced relation with respect thereto, means for feeding a cooling fluid into the opposite ends of said tubular supply member, means 5 for conducting the fluid from the opposite ends of said casing, and means for rotating said fluid supply member and imperforate member relative to the casing.

11. In combination in a fluid cooled roll, an 10 outer cylindrical casing, a tubular fluid supply member arranged within the casing and having a plurality of openings discharging therefrom, said openings being arranged in a plurality of longitudinally extending rows spaced circumferentially of said member, certain of the rows 15 of openings being closer together than other of said rows of openings whereby to effect a relatively greater cooling action upon one portion of the casing than upon another portion thereof, the more closely arranged rows of openings 20 diverging from the opposite ends of the member toward the center thereof, means for supplying a cooling fluid to said member, and means for rotating said member relative to said casing.

12. In combination in a fluid cooled roll, an 25 outer cylindrical casing, a tubular fluid supply member arranged within the casing and having a plurality of openings discharging therefrom, said openings being arranged in a plurality of longitudinally extending rows spaced circumferentially of said member, certain of the rows of 30 openings being closer together than other of said rows of openings whereby to effect a relatively greater cooling action upon one portion of the casing than upon another portion thereof, the more closely arranged rows of openings diverging from the opposite ends of said member toward the center thereof, said member being provided with additional relatively shorter rows of openings 35 interposed between the more closely arranged rows of openings at substantially the center of said member, means for supplying a cooling fluid to said member, and means for rotating the member relative to said casing.

13. In combination in a fluid cooled roll, an 40 outer rotatable cylindrical casing, bearings for rotatably supporting the casing at its opposite ends, a normally stationary fluid supply member arranged within said casing and projecting therebeyond at its opposite ends, means arranged outwardly of said bearings for supporting the opposite ends of the fluid supply member, said member having a plurality of openings discharging into the casing, with the openings being 45 arranged to effect a relatively greater cooling action upon one portion of the casing than upon another portion thereof, means for feeding a cooling fluid into the opposite ends of said member, means for conducting said fluid from the opposite ends of said casing, and means for rotating said member relative to said casing.

14. In combination in a fluid cooled roll, an 45 outer rotatable cylindrical casing, bearings for rotatably supporting the casing at its opposite ends, a normally stationary fluid supply member arranged within said casing and projecting therebeyond at its opposite ends, means arranged outwardly of said bearings for supporting the opposite ends of the fluid supply member, said member having a plurality of openings discharging 50 into the casing, with the openings being arranged to effect a relatively greater cooling action upon one portion of the casing than upon another portion thereof, means for feeding a cooling fluid into the opposite ends of said mem-

ber, means for conducting said fluid from the opposite ends of said casing, means for rotating said member relative to said casing, and means for securing the fluid supply member in adjusted position.

15. In combination in a fluid cooled roll, an 55 outer rotatable cylindrical casing, bearings for rotatably supporting the casing at its opposite ends, a normally stationary fluid supply member arranged within said casing and projecting therebeyond at its opposite ends, said member having a plurality of openings discharging into the casing, with the openings being arranged to effect a relatively greater cooling action upon one portion of the casing than upon another portion thereof, bearing 60 housings arranged outwardly of said bearings for supporting the projecting end portions of said member, each housing being provided with an inlet chamber and an outlet chamber, said member being in communication with the inlet chamber and the casing in communication with the outlet chamber; means for introducing a cooling medium into the inlet chambers, means for conducting the said medium from said outlet chambers, and means for rotating the fluid 65 supply member relative to the casing.

16. In combination in a fluid cooled roll, an 70 outer rotatable cylindrical casing, bearings for rotatably supporting the casing at its opposite ends, a normally stationary fluid supply member arranged within said casing and projecting therebeyond at its opposite ends, said member having a plurality of openings discharging into the casing, with the openings being arranged to effect a relatively greater cooling action upon one portion of the casing than upon another portion thereof, bearing 75 housings arranged outwardly of said bearings for supporting the projecting end portions of said member, each housing being provided with an inlet chamber and an outlet chamber, said member having openings communicating with the inlet chamber, a sleeve encircling the member between each bearing housing and the respective bearing and cooperating with said member to define a passage-way leading from the 80 casing to the outlet chamber, means for introducing a cooling medium into the inlet chambers, means for conducting the said medium from said outlet chambers, means for rotating the fluid supply member relative to the casing, and means for 85 securing the said member in adjusted position.

17. In combination in a fluid cooled roll, an 90 outer rotatable cylindrical casing, a normally stationary tubular fluid supply member arranged within said casing and having a plurality of openings discharging therefrom, said openings extending in a plurality of rows both longitudinally and circumferentially of the fluid supply member and being arranged to effect a relatively greater cooling action upon one portion of the casing than 95 upon another portion thereof, means for supplying a cooling fluid to said member, means for rotating the fluid supply member relative to said casing, and means for securing said member in adjusted position.

18. In combination in a fluid cooled roll, an 100 outer rotatable cylindrical casing, a normally stationary fluid supply member arranged within said casing and having a plurality of openings discharging therefrom, said openings being arranged to effect a relatively greater cooling action upon one portion of the casing longitudinally thereof than upon another portion; means for supplying a cooling fluid to said fluid supply member, means for rotating said member relative to said casing 105

- to localize the greater cooling action upon any desired portion of the casing circumferentially thereof, and means for securing the said member in adjusted position.
- 5 19. In apparatus for producing sheet glass, a pair of rotatable forming rolls adapted to receive a body of molten glass and reduce it to sheet form, each of said rolls comprising an outer rotatable cylindrical casing, a normally stationary fluid supply member arranged within said casing and having a plurality of openings discharging therefrom, said openings being arranged to effect a relatively greater cooling action upon one portion of the casing than upon another portion thereof, means for supplying a cooling fluid to said member, means for rotating said member relative to said casing, and means for securing said fluid supply member in adjusted position.
- 10 20. In apparatus for producing sheet glass, a pair of rotatable forming rolls adapted to receive a body of molten glass and reduce it to sheet form, each of said rolls comprising an outer rotatable cylindrical casing, a normally stationary fluid supply member arranged within said casing and having a plurality of openings discharging therefrom, said openings being arranged to effect a relatively greater cooling action upon one portion of the casing longitudinally thereof than upon another portion, means for supplying a cooling fluid to said fluid supply member, means for rotating said member relative to said casing to localize the greater cooling action upon any desired portion of the casing circumferentially thereof, and means for securing the said member in adjusted position.

JOHN L. DRAKE.
